FIG. 1.

George A. Moyer,
Inventor
By
R. J. Doctor.
Attorney

UNITED STATES PATENT OFFICE.

GEORGE A. MOYER, OF SYRACUSE, NEW YORK, ASSIGNOR TO THE CLEVELAND CANDLE COMPANY, OF CLEVELAND, NEW YORK, A FIRM.

DESIGN FOR A CANDLE.

56,021.

Specification for Design.

Patented Aug. 10, 1920.

Application filed May 18, 1920. Serial No. 382,410. Term of patent 14 years.

To all whom it may concern:

Be it known that I, GEORGE A. MOYER, a citizen of the United States, residing at Syracuse, in the county of Onondaga and State of New York, have invented a new, original, and ornamental Design for Candles, of which the following is a specification, reference being had to the accompanying drawing, forming part thereof.

In the drawings:—

Figure 1 is a view in elevation of a candle, showing my new design.

Fig. 2 is a top plan view.

Fig. 3 is a bottom plan view.

I claim:—

The ornamental design for a candle, as shown.

GEO. A. MOYER.
